ATTORNEY.

UNITED STATES PATENT OFFICE.

CHARLOTTIE GRACE HULSE, OF NEWARK, NEW JERSEY.

DESIGN FOR A FAN.

SPECIFICATION forming part of Design No. 29,165, dated August 9, 1898.

Application filed July 6, 1898. Serial No. 685,291. Term of patent 34 years.

To all whom it may concern:

Be it known that I, CHARLOTTIE GRACE HULSE, a citizen of the United States, residing in Newark, in the county of Essex and State of New Jersey, have invented and produced a new and original Design for a Fan, of which the following is a specification, reference being had to the accompanying drawing, forming part thereof.

The figure shows a plan view of the fan.

As shown in the drawing, the leading and material feature of my design consists of the Cuban ensign and the ensign of the United States, the staffs being crossed and forming a background for a portrait of a naval officer. An eagle with outstretched wings is placed

over the head of the naval officer, the wings crossing the staffs and jacks of the two ensigns.

Having thus described my invention, what I claim as new, and desire to secure by Letters Patent, is—

The design for a fan as herein shown and described.

In testimony that I claim the foregoing as my invention I have signed my name, in presence of two witnesses, this 27th day of June, 1898.

CHARLOTTIE GRACE HULSE.

Witnesses:

CHARLES H. STEWART,
SARAH A. W. ARDREY.
